UNITED STATES PATENT OFFICE.

EDGAR F. ROBINSON, OF ROCHESTER, NEW YORK.

RAILWAY-TIE.

No. 809,940.

Specification of Letters Patent.

Patented Jan. 19, 1909.

Application filed October 12, 1907. Serial No. 397,197.

To all whom it may concern:

Be it known that I, EDGAR F. ROBINSON, a citizen of the United States, residing at Rochester, in the county of Monroe and State of New York, have invented new and useful Improvements in Railway-Ties, of which the following is a specification.

This invention relates to railway ties, and more particularly to that class wherein concrete or cement is employed for bracing or strengthening the shell or trough forming the body portion of the tie, and the object of the invention is to provide a composite tie in a manner as hereinafter set forth and which is so set up as to prevent disintegration due to the pounding and jarring caused by the passage of trains along a railway track, wherein ties in accordance with this invention are used.

A further object of the invention is to provide a tie with means in a manner as hereinafter set forth, which is secured within the body portion and constitutes a support for the track rails as well as acting as a cushioning means therefor.

A further object of the invention is to provide a composite railway tie which shall be simple in its construction, strong, durable, insulated, efficient in its use, obtaining the necessary cushioning effect for the rail sections, readily set up in the track bed, and comparatively inexpensive to manufacture.

With the foregoing and other objects in view, the invention consists of the novel construction, combination and arrangements of parts hereinafter more specifically described and illustrated in the accompanying drawings wherein is shown the preferred embodiment of the invention, but it is to be understood that changes, variations and modifications can be resorted to which come within the scope of the claims hereunto appended.

In describing the invention in detail, reference is had to the accompanying drawings wherein like reference characters denote corresponding parts throughout the several views, and in which:—

Figure 1 is a perspective view of a composite railway tie in accordance with this invention, also showing a rail section attached thereto. Fig. 2 is a longitudinal sectional view broken away of the tie, also showing a rail section connected thereto. Figs. 3 and 4 are transverse sections through the tie, and Fig. 5 is a view of the cushioning block.

Referring to the drawings by reference characters, 1 denotes a U-shaped trough formed of suitable metallic material and which receives a body of concrete, cement or other suitable material as at 2, the said body 2 constituting the body portion of the tie. The body portion 2 is formed of three sections and between the said sections are positioned wooden cushioning blocks 3, the height 65 of the blocks being such as to extend above the top edge of the trough. That portion of each of the side walls of the trough which abuts against the cushioning blocks 3 is perpendicular as at 4, as clearly shown in Fig. 70 3, while the remaining portions of the side walls of the trough which abut against the sections of the body portion incline towards each other as at 5 and as clearly shown in Fig. 4. The inclining of the side walls of 75 the trough provides means whereby the sections of the body portions are retained within the trough.

The tie is provided with an anchoring means for the sections of the body portion 2 80 and such means consists of a series of transversely extending headed bolts 6 which are riveted as at 7. Certain of the bolts are riveted upon one side of the tie while the other bolts are riveted upon the other side of the 85 tie. The cushioning blocks 3 are removably secured in the trough 1 and between sections of the body portion 2 through the medium of the screw-threaded bolts 8, the heads 9 of the bolts 8 bearing against one side wall of 90 the trough while the screw-threaded end 10 of the bolts 8 projects from the other side wall of the trough and carries a lock nut 11 and a cotter pin 13 which bears against the lock nut 11.

Mounted upon each of the cushioning blocks 3 is a rail supporting plate 14 formed with depending pointed studs 15 adapted to enter the block 3 for retaining the plate 14 in position upon the block. Each of the plates 100 is furthermore provided with an opening 16, a transversely extending flange 17 and an opening 18. The track rail section is indicated by the reference character 12 and is mounted upon the plate 14. One side of the base of 105 the rail section abuts against the flange 17. The rail section 12 is secured to the plate 14 by the headed screws 19, the heads 20 of the screws overlapping the base of the rail section. The screws 19 extend through the 110 openings 16 and 18. Projecting upwardly from each of the heads 20 of the screws is a

squared nip 21 for the engagement by a suitable tool to enable the positioning or withdrawing of the screws 19 when occasion so requires. Although the rail sections are 5 secured to the plates 14 preferably through the medium of screws 19 as shown, any other suitable forms of hold-fast devices can be employed.

Preferably the trough is formed of rolled 10 steel and the wooden cushioning blocks creosoted. These blocks form the rail seats, rest upon the bottom of the trough, and upon the blocks as before stated are placed the plates 14 which are shouldered tie plates and prevent the rail section cutting the cushioning 15 blocks and also maintain the gage. The load is therefore transmitted directly from the rail through the blocks to the bottom of the tie and the rail section owing to the 20 height of the blocks in connection with the tie plates is prevented from contacting with the trough at any point. Owing to the foregoing arrangement, the blocks 3 take up the vibration, and turning action is avoided 25 which would not be the case if the rail had a bearing on the side of the trough.

The body portion 2 which is formed of concrete or other suitable plastic material adds weight and strength to the tie and 30 assists in holding the cushioning blocks in position and furthermore forms a solid structure to prevent damage in case of derailed wheels. The bolts passing through the trough hold the elements together and 35 furthermore bind the body portion to the sides of the trough. The heads of the bolts also act as means for pulling the tie into place with hooks when positioning the tie.

What I claim is:—

- 40 1. A composite railway tie comprising a trough having portions of each side wall vertical and the remaining portions angularly disposed with respect to the vertical portions, cushioning blocks mounted between the vertical portions of the trough, a sectional body portion mounted in the trough between the angularly disposed portions of the side walls of the trough, hold-fast devices extending transversely through the side 45 walls of the trough and the cushioning blocks, tie plates mounted upon each of the cushioning blocks, and means extending through the tie plates and engaging in the blocks for securing rail sections to the tie.
- 55 2. A composite tie comprising a metallic trough having each of its side walls provided with vertical and angularly disposed portions, cushioning blocks interposed between said vertical portions resting upon the bottom and of greater height than the side walls of the trough, a sectional body portion interposed between the angularly disposed portions of the side walls of the trough and at each side of the cushioning 60 blocks, a combined tie and gage plate

mounted upon each of the cushioning blocks, said plates adapted to have the rail sections of the track mounted thereon, and means extending through the plates, engaging in the blocks and adapted to engage the base of the rail sections for securing these latter to the tie.

3. A composite railway tie comprising a metallic trough having each of its side walls provided with vertical and angularly disposed portions, cushioning blocks interposed between said vertical portions resting upon the bottom and of greater height than the side walls of the trough, a sectional body portion interposed between the angularly disposed portions of the side walls of the trough and at each side of the cushioning blocks, a combined tie and gage plate mounted upon each of the cushioning blocks, said plates adapted to have the rail sections 80 of the track mounted thereon, means extending through the plates, engaging in the blocks and adapted to engage the base of the rail sections for securing these latter to the tie, means extending through the angularly 90 disposed portions of the side walls of the trough and through the body portion for securing the latter in the trough, and means extending transversely through the trough and blocks for detachably connecting the 95 blocks in position.

4. A railway tie embodying as an element thereof a U-shaped metallic trough having portions of each side wall extending vertically and the remaining portions angularly 100 disposed with respect to the vertical portions, the angular portions of each side wall being so disposed that there is positioned a vertical portion between the center and each end of a side wall.

5. A railway tie embodying as an element thereof a U-shaped metallic trough having portions of each side wall extending vertically and the remaining portions angularly 110 disposed with respect to the vertical portions, the angular portions of each side wall being so disposed that there is positioned a vertical portion between the center and each end of a side wall, a cushioning block interposed between each pair of opposing 115 vertical portions, a composite filling arranged between the cushioning blocks and within the trough, a composite filling arranged at each end of the trough and abutting against the cushioning block, said composite fillings constituting a sectional body portion, and a combined tie and gage plate mounted upon each of the cushioning blocks.

6. A railway tie embodying as an element thereof a U-shaped metallic trough having 125 portions of each side wall extending vertically and the remaining portions angularly disposed with respect to the vertical portions, the angular portions of each side wall being so disposed that there is positioned a 130

vertical portion between the center and each end of a side wall, a cushioning block interposed between each pair of opposing vertical portions, a composite filling arranged between the cushioning blocks and within the trough, a composite filling arranged at each end of the trough and abutting against the cushioning block, said composite fillings constituting a sectional body portion, a combined tie and gage plate mounted upon each of the cushioning blocks, hold-fast devices extending through the trough and cushioning blocks, and hold-fast devices extending through the trough and composite fillings.

7. A railway tie embodying as an element thereof a U-shaped metallic trough having portions of each side wall extending vertically and the remaining portions angularly disposed with respect to the vertical portions, the angular portions of each side wall being so disposed that there is positioned a vertical portion between the center and each end of a side wall, a cushioning block inter-

posed between each pair of opposing vertical portions, a composite filling arranged between the cushioning blocks and within the trough, a composite filling arranged at each end of the trough and abutting against the cushioning block, said composite fillings constituting a sectional body portion, a combined tie and gage plate mounted upon each of the cushioning blocks, hold-fast devices extending through the trough and cushioning blocks, and hold-fast devices extending through the trough and composite fillings, combined with means extending through the gage plates and engaging in the cushioning blocks for securing rail sections to the tie.

In testimony whereof I have hereunto set my hand in presence of two subscribing witnesses.
